I. BIRKELAND

GRAIN STACKER

Filed Oct. 23, 1923

2 Sheets-Sheet 2

UNITED STATES PATENT OFFICE.

INGOLF BIRKELAND, OF FORT BENTON, MONTANA, ASSIGNOR OF THREE-FOURTHS TO
ELIZABETH BIRKELAND, OF FORT BENTON, MONTANA.

GRAIN STACKER.

Application filed October 23, 1923. Serial No. 670,320.

To all whom it may concern:

Be it known that I, INGOLF BIRKELAND, a citizen of the United States, residing at Fort Benton, in the county of Chouteau 5 and State of Montana, have invented a new and useful Grain Stacker, of which the following is a specification.

The present invention has reference to machines especially designed for stacking grain after the same has passed through a heading machine, the primary object of the invention being to provide a machine of this character which will stack the material under treatment in such a way as to cause 15 the same to shed moisture.

Another object of the invention is to provide a device of this character which may be readily and easily controlled by the operator, the operation of the bottom and rear 20 walls of the stacker being purely automatic.

A still further object of the invention is the provision of means operated by the drive wheels of the machine for leveling the grain as it enters the stacker, to insure the 25 true stacking of the material.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a stacker constructed in accordance with the 40 invention.

Figure 2 is an end elevational view thereof.

Figure 3 is a detail elevational view of one side of the stacker.

Figure 4 is a sectional view through one 45 of the hinged doors forming the bottom of the stacker.

Figure 5 is a fragmental sectional view through the end gate illustrating the action 50 of the latch member.

Referring to the drawing in detail, the reference character 5 designates the side

rails of the frame of the stacker which supports suitable bearings 6 that accommodate the shaft 7 on which the bull wheels 8 are 55 mounted.

At the forward end of the machine, are the wheels 9 that may be supplied with a suitable steering mechanism not shown for 60 guiding the stacker.

The body of the machine is box-like in formation and includes the vertical end rails 10 that are connected at their upper ends, by means of the spaced horizontal rails 11, the rails 10 being connected at the 65 ends of the machine by the bars 12. Having connection with the rails 11 are vertical bars 13 that brace the stacker throughout its length and strengthen the body of the stacker against lateral strain directed thereto by the weight of the material thrown thereinto.

Disposed in spaced relation with the bars 12 are horizontal end bars 14 which have connection at their ends with the vertical 70 bars 15 that have downwardly extended portions 16 that are inclined towards the center of the body.

Vertical end bars 16 form parts of the body portion to which bars, plates 18 are 80 secured to provide a rear door, the rear door being hingedly connected to the bars 10 at the rear of the machine, at 19. Carried by the rear door are eye bolts 20 that accommodate one of the ends of the coiled springs 21, the opposite ends thereof having connection with one of the bars 13 at 22, so that when the rear door moves outwardly under the pressure of the weight of the material, in the stacker the rear door will 90 be automatically returned to its initial or loading position.

At the lower end of the door is a lug 23 that is engaged by the latch member 24 pivotally supported intermediate the side walls 95 of the body portion at a point adjacent to the bottom thereof, the latch member being held in its latching position by means of the coiled spring 25. This latch member is supported by the bar 26 that extends longitudinally of the frame of the machine at a point substantially intermediate the side edges thereof, the bar 26 being pivotally supported 100 at its forward end as shown at 27. The rear

end of the bar 26 is beveled as at 26', and is adapted to rest on the inner surface of the rear door.

Thus it will be seen that when the latch member 24 is moved to its inactive position, the bar 26 will drop downwardly under the weight of the material contained in the body portion. A guard plate 28 is secured at the free end of the bar 26 and is designed to engage the ground surface over which the machine is moving, when the doors of the stacker have been moved to release the load, thereby protecting the latch member and preventing the same from contacting with the ground surface as the bar drags.

The movable bottom of the stacker includes hinged doors 29 that are connected to the bar 26 at 30, it being understood that the doors 29 are arranged on opposite sides of the bar 26. These doors 29 include upper sections 31 that are hingedly connected to the upper portion of the stacker at 32 and as shown, are provided with brackets 33 that accommodate the plates 34 that are secured to the door sections 29 to support the door sections 29 in their active positions.

Coiled springs 35 have connection with the upper sections 31 and have their lower ends secured to the bars 13 associated therewith, so that as the sections 31 move downwardly, the springs 35 are placed under tension to return the sections 31 to their normal positions after the weight of the material has been relieved therefrom.

Extending downwardly from the upper sections 31 and secured to the upper surfaces thereof are plates 36 that act as guides to be engaged by the upper edges of the doors 29 to guide the doors to the brackets 33 as the bar 26 supporting the doors, moves upwardly.

Coiled springs 37 are connected with the bar 26 and are adapted to return the bar 26 to its normal position. Positioned at the forward end of the machine are stationary boards 38 that provide supports for the hinged members 39 hingedly connected to the members 38 at 40, the rear ends of the members 39 overlying the forward ends of the doors 29 as clearly shown by Figure 3 so that as the doors 29 move downwardly, the members 39 will also move downwardly. Stops 41 are carried by the members 39 and contact with the under surfaces of the upper sections 31 to restrict movement thereof.

Supported between the rails 11 at the upper portion of the body are horizontally disposed shafts 42 on which are mounted sprockets 43 over which the endless conveyors 44 operate, the endless conveyors 44 being provided with prongs 45 that engage the material thrown into the body of the machine to scatter the material throughout the entire body portion of the machine. These endless conveyors are operated in opposite directions

due to the relation of teeth of the gears 46. At one end of one shaft is a pinion 47 over which the chain 48 moves, the chain also operating over the sprocket 49 which in turn is operated by the bull wheels 8.

The latch member 24 is controlled by the cable 50 that has connection with the latch member 24 at 51, the forward end of the cable extending to a position in proximity to the operator's seat so that the latch member 75 may be readily released by directing a pull to the cable 50.

In the operation of the machine, the machine is driven adjacent to a header spout, of a harvesting machine to discharge the 80 heads into the stacker.

As the body portion of the stacker is filled, the endless conveyors operating at the upper portion of the body, level the material in the body portion. When the body portion is 85 loaded the operator exerts a pull on the cable 50 releasing the rear door and allowing the bar 26 to move downwardly withdrawing the plates 34 from under the brackets 33 and allowing the contents of the body to fall 90 from the machine.

It is obvious that as the doors 29 move downwardly to deposit the material supported thereon, the members 39 also swing outwardly to release such material as is deposited thereon.

Since the doors 29 are normally supported at angles, as the material passes from the body, the material sags or falls downwardly at the sides thereof, forming a crown or 100 water shed at the top of the stack.

What is claimed as new is:

1. A stacker including a body portion having inclined bottom members, a hinged bar extending longitudinally of the body and disposed substantially centrally thereof, said bottom members being hingedly connected to the bar, a hinged door at the rear of the body, means carried by the bar and contacting with the door for normally holding the bottom members and door in their closed positions, means for releasing the door holding means to discharge the contents of the stacker, and means for returning the door and bottom members to their normal positions. 115

2. A stacker including a body portion having inclined bottom members, a bar extending longitudinally of the body portion and having hinged connection with the body at one end of the bar, said bottom members being hingedly connected to the bar, a hinged door at the rear of the body portion, a latch member carried by the bar and contacting with the door for normally holding the door closed, spring members for urging the bottom members and door to their initial positions after they have moved to deposit the contents of the body, and means for operating the latch member. 125

3. A stacker including a body portion, a 130

- bar extending along the bottom of the body portion, said bar being hingedly connected to the body at the forward end of the bar, hinged bottom members connected with the 5 bar, means cooperating with the outer ends of the hinged bottom members for normally holding the bottom members in their closed positions, a rear door for closing the rear of the body portion, a latch member carried at 10 one end of the bar and cooperating with the door for normally holding the door in its active position, means for releasing the latch member, and means for returning the door and bottom members to their active positions. 15 4. A stacker including a body portion, a bar extending along the bottom of the body portion and having pivotal connection with the body portion at its forward end, hinged bottom members supported by the bar, a 20 hinged rear door for closing the rear of the body, a latch member for normally holding the door and bottom members in their active positions, means for releasing the latch member to permit the bottom members and door 25 to move to their open positions, a plate carried by the bar and disposed under the latch member to guard the latch member against contact with the ground surface, and means for moving the bottom members and door to 30 their normal positions. 5. A stacker including a body portion, a bar supported adjacent to the bottom of the body portion, said bar having hinged connection with the body adjacent to the forward end of the bar, bottom members hing- 35 edly connected with the bar and carrying plates at their free ends, hinged upper sections supported by the body, means carried by the hinged upper sections for receiving the plates of the hinged bottom members, a 40 door for normally closing the rear of the body, and means for releasing the door and bottom members to deposit the contents of the stacker. 6. A stacker including a body portion, a 45 bar supported adjacent to the bottom of the body portion, and having its forward end hingedly connected to the body portion, movable bottom members carried by the bar, means for releasing the bar to cause the bottom members to move to their open positions, and coiled springs for returning the bottom members to their closed position. 7. A stacker including a body portion, a 50 bar hingedly connected to the body portion at one end of the bar, a door hingedly connected at the rear of the body portion, a latch member for normally holding the door in its closed position, inclined bottom members hingedly connected to the bar, and 55 adapted to move downwardly with the bar, means for permitting the bottom members to move to their inactive positions, and means gripping the free ends of the bottom members for normally holding them in their normal positions. 60 In testimony that I claim the foregoing as my own I have hereto affixed my signature. 65

INGOLF BIRKELAND.
